JAMES F. MAYS, OF BIRMINGHAM, ALABAMA, ASSIGNOR, BY MESNE ASSIGNMENTS,
TO MAYS ACCOUNTING MACHINE COMPANY, OF ASHEVILLE, NORTH CAROLINA, A
CORPORATION OF NEVADA.

DUPLEX CALCULATOR.

1,115,953.

Specification of Letters Patent. Patented Nov. 3, 1914.

Application filed April 6, 1912. Serial No. 688,912.

To all whom it may concern:

Be it known that I, JAMES F. MAYS, a citizen of the United States of America, residing at Birmingham, in the county of Jefferson and State of Alabama, have invented 5 certain new and useful Improvements in Duplex Calculators, of which the following is a specification.

My invention relates to an improvement 10 in an adding and calculating machine.

I have found that the advantages of the adding machine when used as such independently and more particularly when used in combination with a typewriter in the 15 manner described and claimed in a pending application of even date herewith, are greatly increased by adapting the machine to calculate items of a bill or subtotals on one set of dials and to provide an additional set of totaling dials on which the several items or subtotals may be set up for the 20 grand total and which are disconnected from the operating mechanism of the adding machine when the calculating or sub- 25 totaling dials are being used. To this end I preferably utilize a key controlled operating mechanism for the dials and equip the machine with two sets of dials preferably arranged at opposite ends, there being a 30 coupling mechanism which is controlled by a key or lever and which acts to couple one set of dials to the key controlled mechanism at the same time that it disengages the other set of dials therefrom.

My invention also embodies the novel idea 35 of having a set of number registering dials mounted in the top casing of the machine, and so connected with their actuating mechanism as to be readily detached therefrom 40 and lifted from the machine with the top, and also the idea of having these dials and the keys for operating them so mounted on said top that both said dials and keys may be moved together from the body of the 45 machine on the removal of said top.

My invention further comprises improvements in the keyboard, in the mechanism for carrying from dial to dial of each set of dials, in the means for resetting the dials to 50 zero position, and in various other novel details of construction and arrangement of parts, all of which in their preferred embodiment are hereinafter more particularly

described and claimed, reference being had to the accompanying drawings, wherein:— 55

Figure 1 is a top plan view of my improved duplex adding machine broken away to illustrate in plan various details of the internal operating mechanism. Fig. 2 is a side elevation of Fig. 1, which is also 60 broken away to illustrate the parts of the internal mechanism in side elevation. Fig. 3 is a front elevation which is broken away to illustrate parts of the internal operating mechanism in front elevation. Fig. 4 is a 65 detail view of the key controlled resetting rack. Fig. 5 is a detail view of one of the couplings for connecting one of the dial shafts with the key controlled shafts. Fig. 6 is a detail view of the double pawl forming 70 part of the transmission between the dials and the key actuating mechanism. Fig. 7 is a detail view of the carrying wheel and reset arm.

Similar reference numerals refer to similar parts throughout the drawings. 75

According to the preferred embodiment of my invention the calculating machine is provided with a suitably closed casing through the top of which a series of key 80 posts 1 project for vertical manipulation, each post being surrounded by a coiled spring 2 which is fastened to the top plate 3 of the casing at its upper end and at its lower end is fastened to the post which is 85 provided with a stop pin 4 which arrests the posts when raised by the spring. At an intermediate point each post carries a pin 5 which is adapted to engage a rocker arm 6 which is keyed or otherwise fastened to a 90 rocker shaft 7, a parallel series of which extend from front to rear of the machine and are suitably journaled in bearings 8 formed by vertically projecting parts of metal plates 9 suitably fastened by screws 95 10 to the side walls of the casing. The arms 6 on each shaft increase from rear to front in angular relationship to a common vertical plane, the first rear arm standing in engagement with its respective pin 5 100 while the succeeding arms are each increasingly spaced from their respective pins. This provides a uniform key stroke with a varying angular movement of the rock shafts. Spring retainers 11 project over 105 the shafts and are caught in notches in the

bearings 8 to hold the shafts 7 against vertical movement in their bearings. The lower ends of the key posts 1 are bifurcated and adapted to straddle arms 12 on rocker shafts 13, which are disposed near the bottom of the machine and transversely thereof. These shafts 13 are journaled in metal tongues 14 which are stamped out of plates 9 and bent at right angles thereto so that they stand vertical with a notch or groove in their outer edges which receives the shaft 13. Spring retaining pins 15, similar to 11, serve to hold the several shafts 13 in their respective bearings. By this arrangement the transverse plates 9 serve as bearings for both sets of rocker shafts 7 and 13, there being nine of these plates 9, which are all disposed between the front and rear vertical partition walls 16 and 17, respectively. Between these walls is contained all the key controlled or key operated mechanism, and without going into too great a detail I may state briefly that each mechanism comprises any desired number of rows of numeral keys which are numbered from one to nine in each row from front to rear. The posts 1 of each digit key in a given row will engage a rocker arm 6 on a rock shaft 7 and will, when depressed, rock it through an angle corresponding to the numeral value of the key. The relative movements of the rock shaft, by different keys of a row, may be obtained in the manner described more at length in my Letters Patent No. 842,682, but I prefer the means shown, namely, the varying angular disposition of the arms on each shaft.

Adjustable stop screws 18 are screwed into right angle flanges 19 on the plates 9 and held in adjusted position by set screws 20. Each post 1 carries a stop plate 21 suitably fastened thereto and adapted to engage its respective screw 18 after the keys complete their stroke of uniform length. Each of the rock shafts 7 has its two ends squared and upon each squared end is mounted a coupling sleeve 22 with a squared central opening which makes a free sliding fit on the shaft with which the coupling turns. Each coupling is provided with a peripheral groove 22 and two transverse shift plates 24 are notched so as to make a straddle fit in the groove 23 of each coupling at the front and at rear end of shafts 7. The corresponding ends of these plates 24 are connected by bars 25 and are supported for horizontal adjustment by swinging arms 26. The rear arms 26 are pivotally connected to bearing plates 27 fastened to the bottom of the casing, while the forward arms 26 are keyed to a transverse shaft 28 mounted in bearings 29 fastened to the bottom of the casing. The right hand arm 26 is extended up through the casing and provided with a handle 30 so that when it is swung to the

rear it rocks shaft 28 and, through the other arm 26 thereon, acts to swing the shift frame to the rear, the rear shift bar 24 swinging on its respective supporting arms 26. This causes all of the couplings at the front ends of the shafts to be moved rearwardly to what I term uncoupled position while the rear couplings are slid rearwardly on the shafts 7 into what I term a coupled position, as in this position they will engage the squared ends of alining shafts 31 which have a bearing in and project through the rear division plate 17. These shafts 31 control the operation of the rear calculating dials 32, which are arranged preferably in a raised extension 33 of the casing which has suitable sight openings so as to expose the digits on the periphery of the dials, there being one dial for each rocker shaft 7. In like manner when the lever 30 is moved toward the front of the machine the rear couplings are disengaged from the shafts 31 and the forward couplings engage the squared ends of alining shafts 34, which have a bearing in and project through the front partition wall 16. These shafts 34 transmit movement to the front totaling dials 35, which are disposed at the front end of the machine and have their digits displayed through suitable openings in the top 3 of the casing.

Inasmuch as the transmission mechanism for the front and rear sets of dials is the same, only the operating mechanism for the front dials will be described and this is shown in side elevation in Fig. 2, and partly in plan in Fig. 1. Also since the transmission means from each shaft 31 or 34 to its respective dial are the same, only one such mechanism will be described in connection with a shaft 34 which is journaled at its rear end in the partition 16 and at its forward end in a partition 36 formed by a metal plate suitably fastened to the inner walls of the casing. The shaft has connected to it a coiled spring 37, which is, at its outer end, fastened to partition 16 and which spring tends to rock shaft 34 back to its initial position when moved therefrom by a rock shaft 7, a stop arm 34^a fixed on the shaft 34 will engage a stop 34^b and arrest the shaft 34 in initial position. When the shaft 34 is moved by a rock shaft 7 against the action of spring 37, it turns with it an arm 38 on the outer end of which is pivoted a spring-pressed dog 39 that rides freely over a ratchet wheel 40. The moment the key that operated shaft 7 is released, the spring 37 rocks that shaft back to initial position swinging with it arm 38 and dog 39 which thereupon engages and turns wheel 40 through an angle corresponding to the angle shaft 7 was rocked. This movement of ratchet wheel 40 is imparted to a gear wheel 41 and a stop

wheel 42, all of which are mounted on a common hub which turns freely on shaft 34. A spring catch 43 engages the wheel 42 and prevents inertia movements thereof.

5 Gear wheel 41 meshes with a small gear 44 fixed on a countershaft 45 which is disposed near the top of the casing and is likewise journaled in partitions 16 and 36, through the latter of which an end of it projects and has there mounted thereon a ratchet spider 46. A pair of reversely disposed ratchet pawls 47 are pivoted to the ends of 46 and are pressed by springs 48 against the rear ratchet teeth 49 of a double ratchet wheel 15 which has another set of ratchet teeth 50. This double ratchet is keyed on a shaft 51 which alines with shaft 45 and is journaled in a vertical partition 52 and in the front wall of the casing. The movement of the ratchet wheel will impart a rotary movement to the dial 35 which is likewise keyed on the shaft 51. Between the dial and the partition 52 I fix on the shaft 51 a disk 53 which has a pin 54 passed through it near its outer periphery so as to project on each side. Between the disk and partition 52 I mount freely on the shaft 51 a carrying arm 55 which projects over and rests normally in a notch in the top of partition 52 and has 25 pivotally connected to it a ratchet pawl 56 which rides over teeth 50 of the double pawl when the carrying arm is lifted by the pin 54 in the disk 53 which turns with the dial of next lower denomination to that in question.

30 This lifting of a carrying arm sets its pawl to turn the double ratchet and with it the shaft 51 in question, a sufficient distance to move its respective dial one point, when the arm 55 is drawn back against the partition 40 by a coiled spring 57 which is connected to said arm and the partition 52. The forward end of the pawl 56 carries a rearwardly projecting pin 58 which overhangs a rocker arm 59 pivoted on a stud 60 fixed 45 on partition 52.

50 A spring 61 engages a rear end 62 of the arm 59 and tends to hold it out of engagement with the pin 58. The spring 61 is attached to an angle plate support 63 connected to partition 52 and provided at its outer end with a notch to receive and guide the lower bifurcated end of a key 64, which key straddles a pin 65 fastened in the rear end 62 of the rocker arm 59. The depression of key 64 will raise the rocker arm 59 until it engages pin 58 and raises pawl 56 out of engagement with the ratchet teeth 50 to prevent any carrying operation from dial to dial.

55 Between the disk 53 and the dial 35, I mount freely on shaft 51 a gear wheel 66, which is integral with a hub portion that carries an arm 67. A rack bar 68 engages the gears 66 which are mounted on the several shafts 51 and is supported by flange 65

rollers 69 mounted in angle plates 70 fastened to the front wall of the casing. Near its right hand end the rack is connected by a pin 71 to a lever arm 72, the pin working in a slot 73 in said arm which is keyed on a shaft 74 journaled in the casing and partition 52. Shaft 74 also has a crank arm 75 to which is pivotally connected the shank 76 of a reset key 77. Also a coiled spring 78 is connected to shaft 75 and to the casing at the other end and tends to hold the lever 72 and rack 68 in the position in which said parts will normally stand when a stop 80 on shank 76 engages the casing top. The arms 67 have a spring 79 (see Fig. 7) connected to each of them so that when swung around from right to left by the key imparted movement to the rack, it will spring freely past the pin 54 on the adjacent disk 53 in whatever position the latter may be at that time. But when the rack is given a reverse travel by the action of spring 73, key 77 having been released, the several arms 67 will reverse their swing through a complete circle and then each spring 79, being braced by an arm 67, will pick up its respective pin 54 and will swing the pin, and with it disk 53, shaft 51 and dial 35, back to zero position.

80 If desired coil springs 81 may be connected at one end to each upper rock shaft 7 and to its bearing support so as to assist in rocking the depressed shaft back to normal position with its forward rocker arm 6, engaging the operating pin on the key post 90 of the numeral key "1".

85 The means herein shown and described for supporting the keys 1 and effecting their connection with the rock shafts which they operate, permits of the removal of all of said keys with the top plate of the machine, thus avoiding the necessity of removing the finger pieces or tops of these keys in order to remove said top plate in getting access to the internal mechanism of the machine. The 100 tops of keys 61 and 77 may be removed according to the common practice, in order to lift the top plate from the machine, but the number of these keys is small as compared with the number of keys 1. The dials 32 105 being supported entirely by the extension 33 of the top or cover plate 3 are also removable therewith. One or both sets of dials may be provided with decimal pointer hands 110 115 120 pivotally mounted to the top of the casing.

125 In operation, assuming the rear dials to be coupled up to the rock shafts 7, the depression of any key in a given row from front to rear will swing the rock shaft, corresponding to that row of keys, through a predetermined arc, which angular movement will in turn be imparted to ratchet arm 38. On the release of the key the spring 130 return means on the coupled shafts will

rock arm 38 back to initial position, its pawl engaging and moving ratchet wheel 40 and gear wheel 41 through an arc corresponding to the arc of depression of the rocker shaft 7. This rotary movement of the gear is imparted through the small gear 44 to the upper shaft 45 and rocks the ratchet spider 46, which in turn moves the double ratchet on shaft 51, turning with it the shaft and dial 35. In this manner the depression of the numeral key "5" will advance the dial 35 through five positions or through half a revolution. With each dial moves its respective disk 53 and when the dial nears the completion of a revolution, the pin 54 in the disk will engage and lift the carrying arm 55 on the shaft for the dial of next higher denomination and will raise it in such manner that when the dial of lower denomination completes a revolution and returns to zero position, it will have moved the pawl 56 on the carrying arm into engagement with one of the ten teeth 50 on the double ratchet wheel so that when pin 54 releases arm 55 the spring 57 will draw the arm and pawl down and turn the double pawl and shaft 51 to advance its dial one point. By depressing its respective key 64 this carrying operation will be avoided as the pawl will be held thereby out of engagement with the ratchet teeth 50. To reset the several dials to zero position it is only necessary to press key 64 and release it, whereupon the spring described will swing rack 68 back to initial position, these operations causing gears 66 to swing their "pick-up" springs 78 through a complete circle during which they pass all the pins 54 on the disks, and then back through a circle, during which each will engage the pin on its respective disk and turn the latter with it, thereby moving shaft 51 and dial 35 to zero position. Each of the keys in the calculator keyboard has the same length of travel and offers practically a uniform resistance which permits a much more rapid operation of the machine. Each depression of a calculator key will rock its respective rock shaft 13 through the same arc as it rocks the upper shaft for the objects and for the purposes described in my accompanying application. If it is desired to set up items on the front dials it is only necessary to move the lever arm 30 to the front to cause all the couplings on the forward ends of the shafts 7 to connect the latter with the rocking mechanism for the forward dials and at the same time uncouple the rear dials.

Having thus described my invention, what I claim as new and desire to secure by Letters Patent, is:—

1. A calculating machine having a keyboard, key controlled dial operating mechanism, two independent dial operating mechanism controlled means to connect one set of dials

with said operating mechanism while simultaneously disconnecting the other set, substantially as described.

2. A calculating machine having two complete and independent sets of totaling dials, a common key controlled actuating mechanism for the two sets of dials, and key controlled means to disconnect either set of dials from said operating mechanism, substantially as described. 75

3. In a calculating machine, a casing containing key controlled dial operating mechanism, one set of dials at the forward end of the machine, a second set of dials at the rear end of the machine, key controlled coupling means to connect and disconnect each set of dials to and from said operating mechanism, substantially as described. 80

4. In a calculating machine, key controlled dial operating mechanism comprising a series of actuators, two independent sets of numeral dials, means to couple each set of dials to said actuators, and a key controlled shift means to move said couplings simultaneously to couple one set of dials 90 and uncouple the other to and from said actuators, substantially as described. 85

5. In a calculating machine, a casing, a keyboard, key operated rock shafts, a set of subtotaling dials at the rear end of the machine, a set of totaling dials at the forward end of the machine, independent motion transmission mechanism for each set of dials, coupling means to detachably connect either set of dial operating mechanism to 100 said rocker shafts, and a common shift means to control said coupling means, substantially as described. 95

6. In a calculating machine, a series of rows of keys disposed from front to rear, 105 a series of key operated rocker shafts also disposed from front to rear, a second series of key operated rocker shafts disposed transversely at right angles to the first mentioned rocker shafts, and a series of supporting plates for both sets of shafts, which plates are disposed at right angles to one set of shafts and parallel with the other set of shafts and have lateral projecting portions to receive the latter set of shafts, substantially as described. 110

7. In a calculating machine, an upper set of rocks shafts disposed from front to rear of the machine, a lower set of rock shafts dispesed transversely of the machine, a set 120 of nine bearing plates, arranged transversely of the machine, which at their upper ends receive and support the upper shafts and which have tongues bent out at right angles to receive the lower parallel shafts, means to retain the shafts in their respective bearings, and depressible keys each adapted to actuate an upper and lower rock shaft. 125

8. In a calculating machine, a casing a series of depressible key posts mounted 130

- therein, spring means to hold the posts in elevated position, a stop shoulder on each post, an adjustable stop mounted in the casting and adapted to be engaged by said shoulder to arrest the posts after they complete their substantially uniform down travel, and rocker shafts each having a series of arms which are spaced relatively increasing distances from the arms adapted 5 to be engaged by said posts substantially as described.
9. In a calculating machine, a plurality of rows of keys, there being nine in each row extending from front to rear, a rocker shaft 15 operated by each row of keys and comprising a series of arms adapted to be engaged by the keys, stop shoulders in the same relative position on the keys, and a series of adjustable stop pins with which said shoulders engage at the end of the down stroke 20 of the key, said arms from front to rear on each shaft being spaced a successively increasing distance from the corresponding portions of said keys which are adapted to 25 engage and actuate them, substantially as described.
10. In a calculating machine, a casting having a top cover and two transverse partitions spaced from its front and rear end 30 walls, a series of rock shafts extending from front to rear and disposed between said partitions, bearings in which said shafts are mounted, keys to actuate said shafts, motion transmission mechanism disposed between each end of said mechanisms, coupling means to connect each mechanism with 35 said shafts, and a shift control mechanism for moving all said coupling means to disconnect one set of dials from and simultaneously connect the other set of dials to said 40 rock shafts, substantially as described.
11. In a calculating machine, a series of key operated rock shafts, couplings slidably mounted on said shafts for rotation there- 45 with, dials, motion transmission mechanism connected to the dials comprising shafts which align with the rocker shafts, and a shift plate having a slip connection to the couplings which is adapted to move them 50 simultaneously to connect or disconnect the aligning shafts, substantially as described.
12. In a calculating machine, a removable top plate having a raised compartment for dials with means to expose the dials, dials 55 journaled in said compartment, and key controlled dial operating mechanism with which said dials are detachably connected so as to be lifted out with said top.
13. In a calculating machine, a removable top plate having a raised compartment for 60 dials with means to expose the dials, dials journaled in said compartment, key controlled dial operating mechanism with which said dials are detachably connected 65 so as to be lifted out with said top, and keys
- yieldingly connected to said top plate and removable therewith which are adapted to engage and manipulate said dial operating mechanism when the top is in operating position.
14. In a calculating machine, a dial, motion transmission means connected to said dial and comprising a projection movable with the dial, a gear carrying an arm, a spring connected to said arm, said gear being mounted concentric with the dial and said spring being adapted to snap past said projection when swung in one direction and to engage said projection and move it and the dial when swung back in a reverse direction, and a key controlled sliding rack adapted to rock all said gears back and forth through a circle for the purposes described.
15. In a calculating machine, a series of dials, shafts for said dials, disks keyed on 85 said shafts and having two projections, dial resetting mechanism adapted to engage one projection, and mechanism for carrying from dial to dial which is actuated by the other projection, substantially as described.
16. In a calculating machine, a keyboard comprising depressible keys, and key operated mechanisms comprising two sets of rocker shafts disposed at right angles to each other and having rocker arms, a rocker arm 95 of a shaft in each set being adapted to be engaged and depressed by each key, substantially as described.
17. In a calculating machine, a keyboard comprising depressible keys, and key operated mechanisms comprising two sets of rocker shafts disposed at right angles to each other and having rocker arms, a rocker arm 100 of a shaft in each set being adapted to be engaged and depressed by each key, each key having a shank provided with an intermediate projection for engaging the rocker arm on one of its shafts and at its bottom end adapted to straddle the rocker arm on the other of the shafts adapted to be operated by it, substantially as described.
18. In a calculating machine, a set of dials, a keyboard, an operating mechanism for each dial controlled by the keyboard comprising a ratchet pawl which moves responsive to 115 the depression of the key, a ratchet wheel having two sets of teeth, one adapted to be engaged and moved by said pawl, a spring-pressed carrying arm provided with a pawl adapted to engage the other teeth, said ratchet wheel being connected to its respective dial, and said carrying arm being actuated by the dial of the next lower denomination to advance the ratchet wheel and its dial 120 one-tenth of a revolution for each complete revolution of the dial of the next lower denomination.
19. In a calculating machine, three distinct sets of rock shafts disposed substantially in alinement from front to rear of the 125

- machine, key controlled means to operate the intermediate set of rock shafts, dials movable with the end set of shafts, and key controlled means to operatively connect either end set of shafts with the intermediate set of shafts, substantially as described.
20. A calculating machine, comprising two independent sets of calculating mechanisms operatively disconnected from each other, an actuating mechanism common to both said calculating mechanisms, and means to operatively connect and disconnect said actuating mechanism at will to and from either of said calculating mechanisms.
- 10 21. A calculating machine, comprising two independent sets of calculating mechanisms each having a set of number setting dials operatively disconnected from each other, key operated actuating mechanism common to both of said sets of calculating mechanisms, and mechanism operative at will to connect said actuating mechanism to and disconnect it from either of said calculating mechanisms.
- 20 22. A calculating machine, comprising two independent sets of calculating mechanisms operatively disconnected from each other, actuating mechanism common to both sets of calculating mechanisms, a series of keys operating through said actuating mechanism to set either of said calculating mechanisms, and means to operatively connect and disconnect said actuating mechanism to and from either of said calculating mechanisms.
- 30 23. A calculating machine, comprising two independent sets of calculating mechanisms operatively disconnected from each other,

actuating mechanism common to both sets of calculating mechanisms, a series of keys operating through said actuating mechanism to set either of said calculating mechanisms, means operative at will to connect said actuating mechanism to either one of said calculating mechanisms and simultaneously disconnect said actuating mechanism from the other of said calculating mechanisms.

24. A calculating machine, comprising two independent sets of calculating mechanisms operatively disconnected from each other, a series of rock shafts common to both sets of calculating mechanisms, a series of keys operating through said rock shafts to set either of said calculating mechanisms, and means to operatively connect and disconnect said rock shafts to and from either of said calculating mechanisms.

25. A calculating machine, comprising two independent sets of calculating mechanisms operatively disconnected from each other, a series of rock shafts common to both sets of calculating mechanisms, a series of keys operating through said rock shafts to set either of said calculating mechanisms, and means to connect said rock shafts to one of said calculating mechanisms and simultaneously disconnect said shafts from the other of said calculating mechanisms.

In testimony whereof I affix my signature in presence of two witnesses.

JAMES F. MAYS.
